E. H. FRICKEY

CRUSHER

Filed Dec. 5, 1924

UNITED STATES PATENT OFFICE.

EDWARD H. FRICKEY, OF ST. LOUIS, MISSOURI.

CRUSHER.

Application filed December 5, 1924. Serial No. 754,206.

To all whom it may concern:

Be it known that I, EDWARD H. FRICKEY, a citizen of the United States, and a resident of St. Louis, Missouri, have invented an Improvement in Crushers, of which the following is a specification.

This invention relates to crushers, and with regard to certain more specific features to crushers for such materials as limestone, shale, iron ore, coal, gypsum, asphalt rock and similar materials which may contain moist impurities such as clay or mud.

Among the several objects of the invention may be noted the provision of a simple and rugged crusher, the provision of means for preventing detrimental clogging of such a crusher and the provision of means for easily adjusting the relationship between various elements of said crusher.

The invention accordingly comprises the features of construction, combinations of elements, and arrangements of parts which are exemplified in the structure hereinafter described, and the scope of the application of which will be indicated in the following claims.

In the accompanying drawings, in which is shown one of various possible embodiments of this invention,

Fig. 1 is a right side elevation of the crusher;

Fig. 2 is a front elevation; and

Fig. 3 is a longitudinal section taken on the line 3—3 of Fig. 2.

Similar reference characters indicate corresponding parts throughout the several views of the drawings.

Referring now to the drawings there is illustrated at 1 a frame comprised of side castings 3, a cover 5 and a hopper chute 7.

Forwardly bolted at 9 between the two side castings 3, is a cross channel beam 11 (see Fig. 3). This channel beam 11 serves to tie the side castings together at the forward end of the crusher. Rearwardly a frame 13 serves the same purpose. The frame 13 has its central opening normally closed by a door 15 which may be opened for purposes of inspection when occasion demands.

The cover 5, itself an assembly of component castings, serves to close the device and tie the end castings together at their upper portions.

The side castings 3, the frame 13 including its door 15, and the cover 5 serve to enclose a rotating set of hammers 17 mounted between discs 19. The disc faces are machined to receive the hammers between them and are provided with through-bolts 21 for tightening the hammers. Other holes 23 in the discs permit adjustment of each set of hammers as wear on said hammers takes place. The adjustment is radial so that as the hammers wear shorter, compensation may be permitted.

The discs and hammers are mounted upon a shaft 25 running cross-wise of the machine. This shaft is borne in ring-oiled bearings 27 at each side of the device. The bearings are cast with the end castings and are of generous proportions as is the whole machine. On the left end of the shaft, and outside of the machine is borne the fly-wheel 29, and on its right end the driving pulley 31.

Cradled below the rotary hammers 17 are cage bars 33 cast en-bloc. They are held in position by means of bolts 35 and cage liners 37. The liners are bolted to the side castings 3 and serve as end supports for the cage bars. They also protect the surfaces to which they are bolted from abrasion. These bars serve to permit only material which has been crushed down to a proper size to pass out of the base of the machine.

At the ends of the hammer-disc assembly, or rotor, are placed end liners 39. These are bolted to the end-castings 3 and cover 5 and serve as renewable safeguards against abrasion of said parts.

Forwardly of the machine are mounted the uprights 41 fastened to a foundation and to the machine by suitable means; and trussed together by means of the cross member 43.

At their top, these uprights have mounted between them a shaft 45, borne in adjustable bearings 47. These bearings are fastened to the upper ends of the uprights by suitable slides 49 and rivets 51. Set screws 53 bring about adjustment. The shaft 45 carries sprockets 55.

A shaft 57, similar to the shaft 45 mounted between the end castings, toward their bottom, carries similar sprockets 59. Over the sprockets 55 and 59 are belts 61 comprising links of solid manganese bars. These

links are about twenty inches broad and the two chains or belts of them cover the width of the hammer rotor in projection.

The linked chains or breaker plates 61 and hammers 17 form the crushing elements of this machine. In order to withstand the attendant impact of the crushing operation the chains 61, or breaker plates, are backed by a suitable rugged platen 63. This platen 10 63 is pivoted to the end castings 3 of the frame 1 by means of shaft 65 and backs the breaker plates at the point of impact. It may be adjusted to different required degrees of slope of the breaker plates, or to 15 different degrees of wear in said members by means of the lateral shaft 67 passing through slots in flanges 68 of the platen and slots in the end castings. Outside of the end castings the shaft 67 is bolted at each 20 end to side bars 69 which extend through lugs 71 of the end castings. These side bars may be adjusted by means of nuts and lock nuts 73 so that they may govern the swing position of the platen 63 about its shaft 65. 25 The auxiliary shaft 75 working in slots similar to the above mentioned ones, serves to hold the platen in position by clamping in tension to the end castings.

The hammer shaft 25 is of course driven 30 by means of pulley 31 and at a rate such that the hammers have a linear speed of several thousand feet per minute in the direction shown by the curved arrow in Fig. 3.

The chained breaker plates are slowly 35 driven about four feet per minute by means of a separate motor 77 and worm speed reducer 79, in the direction shown by the straight arrow of Fig. 3. A cleaning scraper 81 keeps the breaker plates free of débris.

The operation of the machine is as follows:

Material such as lump rock is fed into the hopper 7. Gravity carries it downward 45 on the sloping breaker plates into the paths of the rapidly rotating hammers 17. These hammers impact the lumpy material against the slowly moving breaker plate chains 61 thereby breaking most of the material down 50 to a size small enough to pass the cage bars 33. That which has not been broken small enough can not pass the cage bars and consequently goes around with the hammers for a second crushing. The liners 39 protect the frame against wear. The breaker 55 plates of course transmit the force of the blow given to them, to the backing platen 63.

One of the purposes of moving the breaker plates is to provide means for automatically cleaning them. Heretofore, mud, clay or other soft material might and would gather on the stationary plates just clear of the path of the hammers, that is, just above them on the stationary plates. This mate-

rial gradually impacted and gathered in ever increasing quantities and finally materially cut down the capacity of the machine by partially closing the entrance chute. With the present device this disadvantage is eliminated in that the impacting material is gradually brought into the path of the rapidly moving hammers and is thereby scraped off. The scraper 81 furthers this result. This scraper is of particular use 70 when the breaker plate is adjusted to a position some distance from the path of the revolving hammers. This advantage is gained without sacrificing the necessary high relative velocity relationship between the hammers and breaker plate, in so far as the breaker plates move at a relatively slow speed.

In the drawings the hammer type of crusher is illustrated. The improvements 85 herein set forth apply with equal force to gyratory, jaw or roller types.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as 100 illustrative and not in a limiting sense.

I claim:

1. In a crusher of the type described, the combination of rotary crushing elements, an endless chain of movable impact plates cooperating therewith and adapted to receive the impact of blows of said elements on material being crushed, and a platen backing said chain at the point of impact.

2. In a crusher of the type described, the combination of rotary crushing elements, an endless chain of movable impact plates cooperating therewith and adapted to receive the impact of blows of said elements on material being crushed, an adjustable platen backing said chain at the point of impact, and a scraper cooperating with said chain to clean it.

3. In a crusher of the type described, the combination of rotary crushing elements, an endless chain of movable impact plates cooperating therewith and adapted to receive the impact of blows of said elements on material being crushed, an adjustable platen backing said chain at the point of impact, and a scraper cooperating with said chain to clean it beyond the impacting area.

4. In a crusher of the type described, the combination of rotary crushing elements, an endless chain of relatively slowly moving

impact plates cooperating therewith and adapted to receive the impact of blows of said elements on material being crushed, and a platen backing said chain at the point of impact.

5. In a crusher of the type described, the combination of rotary crushing elements, an endless chain of relatively slowly moving impact plates cooperating therewith and adapted to receive the impact of blows of said elements on material being crushed, and an adjustable platen backing said chain at the point of impact.

6. In a crusher, the combination of crushing elements operating at a relatively high velocity, an endless chain of impact plates cooperating therewith and adapted to receive the impact of blows of said elements on material being crushed, and moving at a relatively low velocity in the same direction at

the point of cooperation, and a platen backing said chain of plates at said point of cooperation.

7. In a crusher, the combination of crushing elements operating at a relatively high velocity, an endless chain of impact plates cooperating therewith and adapted to receive the impact of blows of said elements on material being crushed, and moving at a relatively low velocity in the same direction at the point of cooperation, an adjustable platen backing said chain of plates at said point of cooperation, and a scraper for said chain of plates adapted to clean them after they have passed said point of cooperation.

In testimony whereof, I have signed my name to this specification this 3d day of December, 1924.

EDWARD H. FRICKEY.
